[57] CLAIM

The ornamental design for a set of elements for cleaning windshields, as shown and described.

DESCRIPTION

FIG. 1 is a perspective view of the set of elements for cleaning windshields embodying the design of the present invention;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof; and,

FIG. 7 is a bottom view thereof.

The hose portion of the claimed design is shown broken off to indicate indeterminate length.

FIG. 1

FIG. 2

FIG. 3

FIG. 4

FIG. 5

FIG. 6

FIG. 7
